EVACUATORY

Homer Nelson Tweed and Laura Parsons Tweed,
South Pasadena, Calif.; said Homer Nelson
Tweed assignor to said Laura Parsons Tweed

Application June 13, 1934, Serial No. 730,480

7 Claims. (Cl. 4—112)

Our invention relates to the class of hospital apparatus, and has for its object the cleanly evacuation and cleansing of the colon and voiding urine.

To this end, our invention consists generally of a receptor adapted to be held comfortably and closely against the patient's body; a means of preventing splashing of the discharges against the body; adjustable means of fastening the receptor to the bed or other support of the patient's body to maintain close contact of body and receptor; and other valuable inventions and discoveries, all of which are more particularly explained and described in connection with the description of the following drawings, in which:

Fig. 1 is a side view partially in section of the receptor.

Fig. 2 is a front view of the receptor.

Fig. 3 is a side view and partial longitudinal section of the conveyor.

Fig. 4 is a central vertical cross section of the bed type of conveyor.

Fig. 5 is a partial vertical section of the receptor and conveyor.

Fig. 6 is a vertical section on line A—A Fig. 5 of the table type of conveyor.

Fig. 7 is a view of the assembled portable table apparatus.

Fig. 8 is a cross section of a contacting edge 30 of a receptor made of flexible material as rubber.

In Figs. 1 and 2, No. 1 is the receptor shell, No. 2 is the handle of same. No. 3 is an inclined partition, necessary for the support of the male external genitalia during use, and to prevent splashing of same by discharged material, the opening 4 permitting escape of voided urine and passage of a tube to carry fluid for cleansing colon. That portion of the receptor which is applied to the body is shaped to fit same. The edge 13 of shelf 3 passes across the area of the transversus perinei muscles, affording support to the obstetrical perineum against bearing down pressure, and contamination by urine from above. A slope downward toward opening 4 of approximately 15 deg. has been found best. No. 5 is the thickened flat edges of receptor shell 1, ending in a broad, forwardly extending ledge 6, being curved as shown to fit that part of the patient's body. This is very necessary to afford a close contact. Of great importance is the elimination of splashing of the parts about the anus. This is accomplished by the interior lines of that part of receptor 1 lying below shelf 3, as shown. No. 7 is a supporting ledge which rests upon upper edge of conveyor as shown in Figs. 3, 4, 5 and 6

when in use. No. 10 is the downward extension of receptor shell 1, having two semicircular ports 11, 12 giving passage to the exit pipe 24 in Figs. 3 and 4. No. 14 is a locking pin projecting downward from the receptor 1 below the forwardly extending ledge 6 to hold receptor tightly pressed against patient. No. 15 is a threaded boss in which screws a reducer 16 having in it a smooth passage 17 for a small hose. Nos. 18 and 19 are elastic straps used to hold the receptor close to the patient's body in the special bed type of apparatus.

In Figs. 3 and 4, the bed type conveyor has a shell 23 adapted to fit closely around the downward extension 10 of receptor shell in Figs. 1 and 2. No. 24 is the exit pipe adapted to be extended by a rubber hose, not shown. No. 25 is the bottom of the conveyor. A slope of approximately 15 deg. toward exit pipe is essential to prevent splashing and quickly convey discharges to hose. Conveyor and receptor move as one upon a flat surface.

In Figs. 5 and 6 the table type of conveyor is shown as fastened in the wooden table top 29 by screws 30 and 30' passing through vertical edge 28. No. 31 is the level rear portion of the bottom of the conveyor, and 32 is the forward, generally conical bottom of same, sloping to connect with the vertical exit pipe 33. No. 34 is a metal recess fastened in table top 29 a short distance ahead of the conveyor and adapted to receive the pin 14 of receptor in Fig. 1 when receptor is fitted closely against patient's body and locked in position by pin 14 and buttons as 35 in Fig. 7.

In Fig. 7 the table type conveyor of Figs. 5 and 6 is shown as in place in portable type table top 29. In it sets the receptor of Fig. 1. No. 52 is the carrying case for all parts in Fig. 7, except table top 29, and serves as the support for the head end of table top.

The receptor 1 as in Fig. 1 is shown as placed in position in the crotch of human body shown in Fig. 7.

In Fig. 8 the rubber edge 108 is shown as having an extending edge 126 which extends outward as at 127 when not in contact, but doubles back to position 126 when in contact with patient's body 128.

The invention is designed primarily to assist in removing toxic, septic and infective waste from the body by facilitating physiologically complete evacuation of the bowel, at the same time permitting emptying of the urinary bladder. We are aware that there is apparatus used for this purpose.

pose, but all of it falls short of meeting the requirements of comfort and cleanliness important in hospital practice.

Accepting the theory that as much as two hours

- 5 may elapse from the inception of evacuation until its completion, we must provide all means possible harmlessly to promote the act during the time necessary. If the patient is too ill to leave his room, or bed, the apparatus must be carried to him. In all its features it should contribute to the comfort of the patient, for it is a well-known fact that every function is carried on more efficiently when the one directly concerned is comfortable in body and mind.
- 10
- 15 While the use of a padded or upholstered surface for the patient to rest upon is common, the additional special contributions to comfort by the portable apparatus described herein is the principle and application of the leg supports which maintain the legs in the squatting posture, permit complete relaxation of same while free to move without restraint. This squatting, or natural, posture stimulates peristalsis, upon which we must rely for evacuation. Suction to
- 20
- 25 empty colon is inefficient, with the danger of drawing a portion of intestinal wall into apparatus used.

A further feature, shared by all conveyors described herein, is a comfortable close fit to the parts. The sense of pressure imparts such a feeling of assurance of cleanliness that the patient has no misgivings as to accidental soiling of person or linen, relaxation is complete, and discharge is unhindered. A feeling on the part of the patient of insecurity, of actual discomfort and of known uncleanliness has limited the usefulness of much of the available apparatus.

Cleanliness is our first line of defence against septic material. Fissures and abrasions about the anal area are common. Any system of cleansing the colon which does not afford protection against splashing is a direct exposure to infection. Size and mobility of receptor make sterilization by boiling or other means very easy.

45 There are known in the art designs of discharging means for feces and urine, which are held in close contact with the patient's body by attachment to belts or shoulder straps on the body. These arrangements are extremely annoying to nervous patients and interfere with necessary sleep. We show an elastic holding means for the receptor, fastened to the bed on which patient rests, which avoids annoying attachment to the patient.

55 We do not confine the meaning of the claims herewith or later submitted in this case to the particular designs shown in the accompanying drawings, but intend such claims to be broadly interpreted and to cover the use or application 60 of the novel ideas herein explained and illustrated in any form or mechanical design that may be developed during the life of our patent rights.

We claim:

- 65 1. In a receptor for fecal and urinal discharges adapted to be held in contact with the body of a person on a line about both body orifices of said discharges comprising an upright housing that is substantially of inverted U-shape in vertical cross section and D-shape in horizontal section, the front edges of the sides and top wall of said housing being curved so as to conform to the shape of the body around and spaced apart from the fecal and urinal discharge orifices, means within said housing and adapted
- 70
- 75

to fit snugly against that portion of the body between said orifices whereby each of said discharges is prevented from running or splashing the portion of the body exposed in said receptor on the side of said means opposite to each of said discharge orifices and the bottom of said housing having a discharge opening.

2. In a receptor for fecal and urinal discharges comprising an upright housing that is substantially of inverted U-shape in vertical section and D-shape in horizontal section, the front edges of the side and top walls of said housing being curved so as to conform to the shape of the body around and spaced apart from the fecal and urinal discharge orifices, a flexible member positioned on the curved front edges of said side and top walls and adapted to be held in contact with the body of a person on a line about both body orifices of said discharges so as to produce a substantially fluid tight joint between the housing and body, and means positioned close to the part of the body between said orifices adapted to support a scrotum and protect said scrotum from either discharge.

3. In a receptor for fecal and urinal human body discharges a housing provided with a front opening, the edges of which are curved and shaped so as to conform to the shape of the body around and spaced apart from the fecal and urinal discharge orifices of the body, a flexible member secured to the curved edge of said housing and adapted to be held in contact with said body on a line about said body discharge orifices, and a comparatively rigid supporting means attached to said edges near said line.

4. In a receptor for fecal and urinal discharges an upright housing that is substantially of inverted U-shape in vertical section and D-shape in horizontal section, the front edges of the side and top walls of said housing being curved so as to make continuous contact with the reclining body of a person on a line about both body orifices of said discharges, means whereby each of said discharges is directed away from its respective orifice when said person is reclining on his back.

5. In a device of the character described, the combination with a base provided with a discharge opening, of a receptor mounted for sliding movement on said base, said receptor comprising a housing that is substantially of inverted U-shape in vertical section and substantially D-shape in horizontal section, the front edges of the side and top walls of said housing being curved so as to conform to the shape of the body around and spaced apart from the fecal and urinal discharge orifices and cooperating means between the lower portion of said housing and said base whereby said housing may be detachably secured in a predetermined position upon said base.

6. In a device of the character described, the combination with a base provided with a discharge opening, of a receptor mounted for sliding movement on said base, said receptor comprising a housing that is substantially of inverted U-shape in vertical section and substantially D-shape in horizontal section, the front edges of the side and top walls of said housing being curved so as to conform to the shape of the body around and spaced apart from the fecal and urinal discharge orifices and a handle on the rear portion of said housing.

7. In a receptor for fecal and urinal discharges, a housing that is substantially of inverted

5 U-shape in vertical section and substantially D-shape in horizontal section, the front edges of the side and top walls of said housing being curved so as to conform to the shape of the body, around and spaced apart from the fecal and urinal discharge orifices, a partition disposed between the intermediate portions of the side

walls of said housing, which partition declines toward the rear of the housing and there being a discharge opening formed in the lower rear portion of said partition.
